UNITED STATES PATENT OFFICE

156,993

PORTABLE DRINK DISPENSER

Robert A. M. Peterson, New York, N. Y., assignor to Peterson Enterprises, Inc., New York, N. Y., a corporation of New York

Application May 17, 1948, Serial No. 146,419

Term of patent 7 years

(Cl. D2—3)

To all whom it may concern:

Be it known that I, Robert A. M. Peterson, a citizen of the United States, residing in the city of New York, county of New York, and State of New York, have invented a new, original, and ornamental Design for a Portable Drink Dispenser, of which the following is a specification, reference being had to the accompanying drawing, forming part thereof, and in which

Figure 4 is a fragmentary top perspective view of the dispenser with the harness omitted and with the dispenser broken away for convenience of illustration.

The dominant features of my design reside in the portions shown in full lines.

I claim:

The ornamental design for a portable drink dispenser, as shown and described.

ROBERT A. M. PETERSON.
